UNITED STATES PATENT OFFICE.

JACOB WILLIAM LATTIG, OF BETHLEHEM, PENNSYLVANIA, AND CHARLES L. GOODRUM, OF NEW YORK, N. Y., ASSIGNEES TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

Original application filed August 29, 1904, Serial No 222,657. Divided and this application filed October 12, 1917. Serial No. 196,125.

To all whom it may concern:

Be it known that we, JACOB W. LATTIG and CHARLES L. GOODRUM, citizens of the United States, residing at Bethlehem, in the 5 county of Northampton and State of Pennsylvania, and at New York, in the county of New York and State of New York, respectively, have invented certain new and useful Improvements in Automatic Telephone-Exchange Systems, of which the 10 following is a full, clear, concise, and exact description.

This invention relates to telephone exchange systems employing machine switch- 15 ing and common battery working, that is to say, a system wherein a single source of current at the central office is used both for setting the switches and for furnishing current to the transmitters for talking pur- 20 poses, and is a division of an application of Jacob Lattig and Charles L. Goodrum, filed August 29, 1904, Serial No. 222,657.

One of the features of this invention is the provision of a circuit arrangement 25 wherein the talking current is fed to the transmitters of a pair of interconnected telephone lines over the windings of a pair of relays which are maintained energized by such current as long as the talking 30 circuits, including the transmitters, are closed, and when either of such circuits is opened, as by the replacement of the receiver of either party to the connection, the consequent deenergization of the corresponding 35 relay renders operative the restoring means of the automatic switching apparatus over which the connection was built up.

Another feature of the invention is the provision of a circuit arrangement for a 40 system of the character set forth, wherein talking current is supplied through only two relay windings to the transmitter of the calling line, and whereby the same kind of current is also supplied through only 45 two relay windings to the transmitter of the called line, none of said relays being individual to the called line. More specifically, this feature consists in a circuit arrangement for machine switching systems 50 wherein, as the selectors are set in building up the connection, the bridging relays used in setting such switches are suc- 55

sively cut off, the pair of control relays of the connector or the last switch in the train being left bridged across the talking conductors, through which relays talking current is fed to the calling line, the transmitter of the called line being provided with talking current through the windings of a similar pair of relays bridged across the 60 talking conductors of the connecting circuit. The calling and called ends of the connecting circuit are conductively separated but inductively united by a pair of condensers, included in the talking conductors 65 between said pairs of relays.

Our invention is illustrated in the accompanying drawings, wherein the same letters of reference point out the same parts throughout. In these drawings, 70

Fig. 1 is a diagram of a subscriber's line and substation apparatus, together with the first selector for that line, and its contacts in multiple banks of various connectors; Fig. 1^a is a diagram of a trunk circuit 75 leading from a first selector to a second selector or a connector; Fig. 2 is a diagram of the circuits of a second selector; Fig. 3 is a diagram of the circuits and connections of a connector; and Fig. 4 is a diagram of 80 a subscriber's line, its substation apparatus, and its first selector, the connection to the multiple bank of the connector of Fig. 3 being shown in heavy lines at the left.

In reading the following description, it 85 should be noted at the outset that the figures join onto each other in sequence, the division line in each case being between the wipers and the wiper contacts of the switches. Thus the wipers on the right of Fig. 1 90 are supposed to be a part of the same switch and to align with the contacts on the left of Fig. 2, and so on. In order to render the reading easier, the figures should be put together as thus indicated. 95

We have not illustrated the switch mechanism in detail as regards its mechanical parts, more particularly because our invention is not limited to a specific switch, but may be practiced with any one of a number of automatic switches. As the circuits are shown, however, for the sake of illustration we will refer to the following 100 patents, in which the so-called Strowger

type of switch is shown, this being with some modifications hereafter referred to, adapted for use with these circuits. The patents are: 591,201, Oct. 5, 1897, Strowger, 5 Lundquist and Erickson; 638,249, Dec. 5, 1899, Keith and Erickson; 672,942, Apr. 30, 1901, Keith and Erickson.

We do not illustrate the apparatus at the subscriber's station for the reasons already 10 given. Here also our invention may be practiced with several types of apparatus, although for the sake of illustration here we have shown the well-known Strowger type of apparatus.

15 Before proceeding to detailed description, we will state the parts and functions of the apparatus which we here show, the circuits for the same, and the modifications therein caused by the application thereof to our 20 purposes.

In this system all talking circuits are metallic, that is are composed of two line wires; and in addition we employ a ground return. Each line comes into central and 25 is there connected to its first selector, corresponding to the answering jack of a manual multiple switchboard, and also is connected to multiple contacts in the several banks of connectors, to which reference will presently 30 be made.

Each selector switch is a self-contained unit individual to its line, and each contains a multiple contact for each of the second 35 selectors (in an exchange over 1000) or for each connector (in an exchange under 1000). Each second selector is also a self-contained unit, connected to its various multiples in the first selectors either direct or through a trunk line, and each contains a multiple contact in its banks for each connector. Each connector is a complete switch unit connected to its multiples in the various second selector banks (in an exchange over 1000) or to the multiples in the first selector banks 40 (in an exchange under 1000), and each connector contains in its banks contacts for the subscribers' lines falling within its range, usually from one-hundred division to another.

50 The mode of selection of a wanted subscriber, roughly stated, is as follows: The calling subscriber (in an exchange over 1000) works his first selector (which is permanently associated with his line) to 55 connect with an idle second selector in the set containing the thousands terminals corresponding to the thousands digit in the number wanted; this cuts off the first selector magnets, whereupon he works the 60 second selector switch in a similar manner to the first to put himself in connection with the terminal contact of an idle connector in the hundreds group corresponding to the hundreds digit in the number wanted; this 65 cuts off the second selector magnets, where-

upon he works the connector switch to select a multiple terminal of the particular line wanted. As the connection progresses step by step, the metallic talking circuit is correspondingly extended through the first 70 and second selectors and the connector, unbroken to the latter, but therein separated by condensers. The main battery is bridged across this circuit on the end toward the called subscriber, but until the latter answers there is no bridged battery on the calling end. All the signaling is done over one or the other line wire and the ground. The connection being completed (that is the line wanted not being found busy) the calling subscriber pushes his button and a ringing relay in the connector circuit throws ringing current on the wanted line. When the called subscriber answers he automatically works relays in the connector circuit which cut back the main bridged battery on the calling end of the talking circuit. When the conversation is finished and the subscribers have hung up their receivers, a release magnet in each of the intermediate 90 circuits trips the mechanism and all of the switches are restored to normal.

Fig. 1 shows a pair of line wires 1-2 constituting a subscriber's line circuit and extending out from the first selector or individual line switch S to several subscribers' stations. A, A', A² and A³. The station A is shown in full, connected to the line wires 1 and 2 by the branches 3 and 4. The stations A', A² and A³ are all the same as station A, each being connected across the line by its own pair of branches 5-6, 7-8, or 9-10. The line 1-2 therefore is a party line, and as will appear later the stations are adapted to be signalled selectively. At 105 each subscriber's station a transmitter T, a receiver R, an induction coil I, a switch-hook H, a ringer Q and condenser C, are provided. In addition to these any suitable impulse transmitter is mounted on the 110 set, preferably to work with the other apparatus shown, a transmitter of the Strowger type so arranged as to have successive movements, each movement transmitting a digit less in value than 10. Each 115 transmission sends the desired number of impulses over the vertical side of line, and then a single impulse over the rotary side of line. It may be well here to explain the meaning of these terms vertical and rotary. In connection with the Strowger switch they have a specific significance, but in our specification they are used for convenience, and not as a limitation to a 120 Strowger switch. In this switch there is a vertical spindle v (see Fig. 1) carrying wipers or contact springs v' and v² which are adapted to pass over and make connection with bank contacts m' and m². These 125 bank contacts, as shown in the patents here- 130

inbefore referred to are arranged in horizontal rows of ten or more each (in the present case ten). The banks of rows are bent in semicircular form with the center 5 of their radii in the axis of the vertical spindle v . In order to bring the wipers into contact with any particular contacts m' and m^2 therefore the spindle v is first stepped up until each wiper is opposite the desired 10 row, and then is turned around step by step until the wipers come in contact with the desired particular terminals in the row. The first movement of the spindle is called the vertical movement, and the second the 15 rotary movement. From these two descriptive terms the words vertical and rotary have come to be applied to the two line wires, although in the present system, as will appear later, the selecting impulses are 20 all sent over the vertical side of line. This vertical side is marked 11 in Fig. 1, 13 in Fig. 2, 15 in Fig. 3 and 17 in Fig. 4. The rotary side of line on the other hand is marked 12, 14, 16 and 18 in Figs. 1, 2, 3 25 and 4 respectively. The terms will be employed herein for convenience to designate the two line wires, while the various magnets and other parts of the apparatus will be designated as vertical and rotary to dis- 30 tinguish their functions.

Returning to the subscriber's station A, we have said that the transmitter should send selective impulses over the vertical side of line, and a single impulse at the end of 35 each group over the rotary side. This is accomplished by transmitting wheels acting in conjunction with certain groups of contact springs $a, a', a^2, a^3, a^4, a^5, a^6, a^7, a^8, a^9, a^{10}, a^{11}, a^{12}, a^{13}, a^{14}$, and a^{15} , together with 40 the hook lever H. The functions of these several springs will appear more particularly from the statement of operation here- after.

The receiver R is shown in a local circuit 45 21 terminating in one winding of the induction coil I, this being in effect the same as cutting off the receiver by a condenser so that battery current will not flow through it and its resistance is removed from the line. 50 The transmitter circuit for the common battery system may be traced as follows: From vertical line wire 11 by branch 3, wire 25, spring a , wire 26, spring a^5 , spring a^6 , wire 24, springs a^{14} and a^{15} , line winding of induction coil I, transmitter T by wire 23, and thence by wire 22, springs a^8 and a^9 and wire 55 21 to the rotary side of line 12, through the branch 4.

The ringer Q is in a ground tap from 60 branch 4 on the rotary side of line, with an interposed condenser C. The spring a^4 is grounded at G through a resistance r , for a purpose to be presently disclosed.

It is to be understood that no substantial 65 change is required in the subscriber's instru-

ment to convert this system back into a local battery system, the apparatus remaining the same and the only changes being in the receiver and transmitter wiring.

Passing to the central office, the metallic 70 talking circuit wires 11 and 12 pass through the first selector S, and terminate in the switch arms f' and f^2 of what we shall designate as the "side-switch" F. This side-switch comprises four arms moving together over a 75 series of contacts, there being three contacts for each arm. These arms are lettered respectively, f, f', f^8 and f^2 . Arm f plays over contacts, f^0, f^{10} , and f^{20} , being normally in contact with f^0 . Similarly and synchronously the other arms move over their corresponding contacts during the operation of the apparatus, being normally in contact with the point f^0 in each case.

The vertical wire 11 is normally connected 85 through arm f' and wire 30 to the vertical relay D, thence by wire 31 through the cut-off springs k^3, k^2 and k' through wire 32 to the grounded main battery B. The rotary wire 12 is normally connected through arm f^2 by 90 wire 34 to the rotary relay E, thence by wire 33, springs k^2 and k' , and wire 32 to the same battery.

In their normal condition it is apparent 95 that the wires 11—12 are severed from the wipers v' , and in the severed conductors leading from the contacts f^{20} to the wiper contacts v' , we interpolate the two equal and opposite windings of a differential relay O, shown in the diagram as having an armature 100 o adapted to close upon a contact o' , connected by wire 35 with the busy-switch U, through the contacts u and u' thereof to the bridge cut-off magnet K, and by wire 32 to the main battery. The armature o is connected on the other side by wire 36 to the private contacts m^{10}, m^{12}, m^{14} and m^{16} in the several banks allotted to the various parties on the line. We should state that this differential relay is used in connection with party 110 lines only. Its winding and connections are such that under normal conditions of current flow in the metallic circuit the armature remains unaffected, and the alternating currents encounter no substantial retardation, 115 either because of twin winding or of a copper jacket.

The vertical relay D controls through its armature a contact spring d to close the same on a ground contact g . Spring d is connected 120 by wire 37 through the springs p^2-p' and wire 38 to the vertical magnet D' (which actually does the vertical moving of the spindle v) thence by wire 39 to the main battery wire 32.

The relay E through its armature controls a spring e adapted to close on the same ground contact, spring e being connected by wire 390 to the private magnet P and thence to the main battery wire 32. From the wire 130

390 branch 40 extends to the second contact f^{10} of the side switch arm f^2 . When the arm f^2 is on this contact the circuit would be continued through the back release relay J to the private contact v^2 . Normally however this magnet is cut off.

The magnet J through its armature j controls the spring contacts j^1 and j^2 , which when the armature is attracted ground the wire 41 of the release magnet I , which is connected through wire 42 to the main battery wire 32. It will be observed that the armature of the private magnet P controls the springs p^1 , p^2 and p^3 the latter two of which 15 also control a ground connection for the magnet I by way of wire 37 and spring d . It is necessary however that both magnets D and P be energized in order to close this circuit, and as P is controlled by E , this means 20 that both vertical and rotary relays D and E must be energized.

Although a controlling means is not shown in the drawing the magnet P controls the side-switch F . When the restoring magnet I permits the parts to return to normal, the switch arms of switch F are all returned to the position shown in Fig. 1. At each retraction of the armature of magnet P these switch arms are all advanced one step by 30 means of an escapement controlled by the said armature. This will be referred to again in the statement of operation.

Before leaving Fig. 1 reference should be made to the magnets L and N , and also to 35 the arrangement of multiples shown. The magnets L and N are register magnets, and the multiples shown are arranged for party line signaling. In considering both of these let us glance first at the general lay-out hereinbefore stated. It will be remembered that 40 each line has a first selector such as shown in Fig. 1. This first selector not only has the individual selective contacts v' , corresponding to the answering jack, but it also has multiple contacts m' , etc., with which 45 these selecting contacts operate. These multiples m' represent the terminals of wires 13 and 14 leading to the various second selector switches. These correspond to trunk lines 50 in a manual exchange, and as they are only used at any one time by a limited number of subscribers, they are much fewer in number than the lines of the first selectors, say amounting to ten per cent thereof. The 55 same may be said of the connectors, which are further extended trunks. Now the multiples m' in the first selectors represent second selectors, and the multiples in the second selectors represent the connectors. 60 The multiples in the connectors however directly represent and are connected to the subscribers' lines and their first selectors. In the drawings Fig. 3 shows a connector. The multiple contacts m^5 on the connector for the line 19-20 appear in Fig. 4. The same

connector would contain a pair of multiple contacts as say m^9 corresponding to the line 1-2, provided the said line 1-2 fell in the same hundreds division, to which that connector is appropriated. This furnished the 70 key for our selective party line system. Observe the multiple contacts $m^9-m^{11}-m^{13}$ and m^{15} belonging to the line 1-2 are distributed so as to be located in different connectors. The connectors are arranged in 75 groups, and since we use the decimal system in the present case for convenience, each group has the multiple terminals of subscribers whose numbers all have the same hundred digit. Thus there will be one group 80 of connectors for subscribers from 1 to 100, another group for those from 101 to 200, another from those from 201 to 300, and so on. In the same way the second selectors are divided into groups according to the 85 thousands, and each second selector has multiple terminals for all the connectors within its thousand. Thus there will be multiples in one group of second selectors for all the connectors between 1 and 1000, that is 100, 200, 300, and so on to 900, which within 90 itself selects up to 999. Of course as already stated if the exchange is limited to 1000 or less the second selectors can be dispensed with. In each first selector then every horizontal row of contacts would represent a 95 separate hundred, and each contact in that row a separate connector in that hundred group, all the connectors in one group being duplicates. To select a given line the first 100 selector is worked to select the thousands or the hundreds group required, and finally the connector is worked to select the line. By preference we put the ringing generator connections in the connector circuit, and since 105 the connectors are in groups we can give each of several groups different varieties of current for ringing, or differently connect the generators as from one side of the line to ground or from the other side to ground. Referring now to Fig. 1 which shows a party line having four telephones, instead of 110 simply multiplying the line to its normal set of terminals as m^9 in the first hundred bank of connectors (assuming its number 115 we will say to be 12), it is multiplied to the number 12 terminals in the first hundred bank of connectors, to the number 12 terminals in the second hundred bank of connectors, to the number 12 terminals in the third 120 hundred bank of connectors, and to the number 12 terminals in the fourth hundred bank of connectors. The bells at stations A , A' , A^2 and A^3 are all in ground taps from the 125 rotary side of line, each with a condenser, and each adapted to respond to a different frequency of ringing current. A to 20 cycle current, A' to 40 cycles, A^2 to 60 cycles and A^3 to 80 cycles, for ringing. Four generators are provided at the central office, giv- 130

- ing respectively 20, 40, 60 and 80 cycle current. Every first hundred group of connectors derives its ringing current from the 20 cycle generator, every second hundred group 5 of connectors derives its ringing current from the 40 cycle generator, every third hundred group from the 60 cycle generator, and every fourth hundred group from the 80 cycle generator. It will be understood 10 therefore that the multiple contacts m^9 , m^{11} , m^{13} , and m^{15} accompanied by their private or busy contacts m^{10} , m^{12} , m^{14} and m^{16} , are distributed in the four groups of connectors referred to, and any station on this line 12 can 15 be selectively rung by selecting the proper hundreds group of connectors and then getting number 12. This means that in the present case subscriber A would be called as number 12, subscriber A' as number 112, subscriber A² as number 212 and subscriber A³ as number 312. The calling subscriber exercises no judgment in the matter, but simply takes the number as he finds it in the directory, and works his calling dial accordingly. 20
- It should be noted that by this arrangement the number of individual or first selector switches is not increased at all. Neither is there any increase in mechanism in any of the switches, the only change being that each party line appears in as many groups of connectors as there are subscribers on the line, and each subscriber has his own independent number. 25
- Means are hereby provided whereby any subscriber on the line can call any other, and in fact it is quite possible for a subscriber to ring his own bell by selecting back his own station, even with the receiver off the hook. 30
- Referring now to the call registers, attention is first directed to the fact that we have here double connections for each line, those to the first selector switch corresponding to the answering jack, and those to the 35 multiples in the connectors, corresponding to the multiple jacks in a manual multiple board. We state this analogy because we consider our invention need not be limited to an automatic system, being equally applicable to a manual system. We shall not describe such a system at length because we do not consider it necessary, for any person skilled in the art will be able to apply the invention from the following description. 40
- There are two classes of calls we wish to register, in-coming and out-going, that is those which originate at other stations but for any reason are "reversed," and those originating at the home station, respectively. Hence we provide two registers, and since out-going calls use the first selector or answering jack switch, we put the corresponding register in the circuit of that switch, by means of a branch 421 of the rotary wire 12. It is true that the magnet L 45
- is thus included directly in the talking circuit, but its impedance may be neutralized by a copper jacket, or it may be shunted by a non-inductive resistance r' , which will pass voice currents without much drop, while barring signaling currents and forcing them through the relay. 50
- In-coming calls come over the multiples, hence we put the in-coming or neutral relay N in a branch 43 in series with the connections to the multiple contacts, from the rotary wire 12, the other connection from wire 11 being made by branch 44. 55
- Having thus described the apparatus and circuits of Fig. 1 in general, we will pass to the second selector and connector figures, and the trunk line. Fig. 2 shows the second selector. After this has been selected by the first selector, the controlling magnets and apparatus of the latter are cut out, the 60 switch-arms of switch F pass onto their third contacts f^{20} , and the metallic circuit 11-12 is continued through to the conductors 13-14 by way of the contacts $v'-m'$, as indicated in heavy lines. The operation of the impulse transmitter at the substation is repeated to affect the vertical and rotary relays D² and E² of the 2d selector. The side switch F' of this selector is normally forced over with its arms f^1 , f^5 , f^6 , and f^7 on their first contacts f^0 , as before. The wire 13 is connected through a branch 45 with the magnet D² and thence to the main battery wire 32. The rotary wire 14 is connected by branch 46 to the magnet E² and thence to the battery wire 32. The armature of magnet D² controls a spring d' and a mechanically connected but electrically insulated spring d'' which latter closes on the ground contact g' when the armature is attracted. 70
- The armature of magnet E² controls a spring e' and a mechanically connected but electrically insulated spring e'' which latter closes on the ground contact g' when the armature is attracted. The two springs d' and e' have curved ends adapted to come together when both armatures are simultaneously attracted at the point marked x , but not when either armature is attracted alone. When these close together 75
- they complete the circuit for releasing the two selectors by magnets J and J', through the path: Battery B, wire 32, 50, J', 51, 48, e' , x , d' , 47, 49, m^2 , v^2 , 52, J, 53, f^3 , f^{20} , and ground back to battery. Operated by itself 80
- the magnet P² controls the circuit of the vertical magnet D² which also passes through the contacts of the private relay P², the latter controlling the escapement of the side switch F', as in the first selector. When 85
- the single impulse comes over the rotary side of line as before, this private magnet breaks the vertical magnet circuit, the side switch moves a step to cut in the rotary magnet E², and the latter acts continuously to rotate 90
- the selector. 95

the switch, as in the first selector, until cut out by the final movement of the side switch to its third contacts and the completion of the talking circuit past the switch.

5 The second selectors are intermediate links, in the nature of trunk lines, and we have reduced the mechanism therein to its simplest possible form. At the same time it is to be understood that we may employ the 10 second selector circuit instead of the connector circuit for various purposes, such as selective party line ringing. Thus, instead of numbering the subscribers on one line so that they fall in different hundreds and 15 hence in different connector groups, we may number them so that they will fall in different thousands, which brings them into different groups of second selectors, working back through the connectors. Thus the 20 ringing may be done from the selector circuits if desired.

Referring to Fig. 3, we will describe the connector apparatus, and then will outline the operation of our entire system. In the 25 first place it will be observed that the wires 15 and 16 which constitute the talking circuit through the connector are not electrically continuous, as they are in the first and second selectors, but are separated in 30 the middle by condensers CC'. The purpose of this will presently appear. It may generally be stated that such separation enables the control of battery current over one side or the other, from one station or the other, 35 for signaling, recording, and the like.

As a matter of convenience, we have designated the two ends of this connector circuit as 15—16 and 15'—16', respectively. Connected from the wire 15 by branch 55, is the 40 vertical relay D⁴, joined on the other side by wire 56 to the spring 57 of a cut-off relay V. This spring is normally in contact with springs 58 and 59, the former connected by wire 61 with the spring 62 of the ringing 45 relay W, normally in contact with spring 63 from which wire 60 leads to the rotary relay E⁴, and thence to the rotary side of the line. The spring 59 also goes to battery B. The 50 relays D⁴ and E⁴ are thus bridged across the wires 15—16, the wire 60 being connected to 16. V' is a cut-on relay, the function of which will presently appear.

The vertical relay D⁴, through its armature, controls spring d³, and the mechanically connected but electrically separated spring d⁴, the latter closing upon the ground contact g². The rotary relay E⁴, through its armature, controls a spring e³, and an electrically insulated but mechanically connected 55 spring e⁴ also adapted to close upon the ground contact.

It will be remembered from the previous statements that the connector not only steps up its wiper v⁵ to the desired row of contacts m⁵, but also steps around the wiper

to the desired line contact. Hence we have the vertical magnet D⁵, which does the vertical stepping, controlled by the relay D⁴, its circuit passing from the spring d⁴ by way of the wire 64, through the normally closed springs p², p¹ of the private magnet P², by wire 65 to the arm f⁴⁰ of the side switch F², thence by wire 66 to the magnet D⁵, and by wire 67 to the main battery wire 70 32. The first succession of impulses over the vertical wire 15 works the magnet D⁵ through the relay D⁴. This places the wipers vertically. The single impulse over the rotary wire then closes the private magnet circuit, steps the side switch F² around one contact with all its arms f⁴⁰, f⁵⁰, f⁶⁰, f⁷⁰. This substitutes for the vertical magnet D⁵, the rotary magnet E⁵. The final selective impulses over the vertical wire 15 then work the relay D⁴ and the magnet E⁵ to bring the wiper v⁵ on the contacts m⁵ of the line 19—20 wanted. This series of impulses is followed by a single impulse as before, over the rotary side of line, which again actuates the private magnet and this moves the side switch F² into its third position so that its four arms rest upon their last contacts f²⁰. The arms f⁵⁰ and f⁶⁰, it will be observed, have completed the talking circuit (marked in heavy lines), and the rotary and vertical magnets are entirely cut out. The ringing relay W, however, is cut in by way of wire 69 and contact f²⁰ through wire 65 back to the contacts of relay D⁴. When the calling subscriber 80 90 has gone thus far, he presses his ringing button, and thereby grounds the vertical side of line once more. This energizes the relay D⁴, completing a circuit from ground through springs g² and d⁴, wire 64, springs p² and p¹, wire 65, side-switch arm f⁴⁰, side-switch contact f²⁰, wire 69, and relay W to battery. This energizes the ringing relay W, which breaks the through talking circuit 95 and connects the ringing generator wire 170 through the spring 71' to the rotary wire 16' on the called side of the break, and so to the wire 18, the ringer Q' and ground. 100 110

The two magnets V and V' are bridged across the line, with the main battery interposed. They both receive current when the called subscriber answers, this flowing over the metallic circuit 15'—17, 19—station A⁴—20—18—16', and back to battery. The cut-on relay V' is adapted to complete a bridge 115 across the calling end of the line, including the battery B and the relays X and Y, by the following path: battery B, wire 71, magnet Y, wire 72, spring 73, spring 74, wire 75, wire 16, back to the calling subscriber's station through the wires 14 and 12, out again through the wires 11 and 13 to the wire 15, and by wire 76 to spring 77, spring 78, wire 79, magnet X, and ground back to the battery. When the magnet V' is energized, this 120 125 130

bridge circuit is completed and the battery is put on the calling subscriber's line. At the same time, however, we cut off the magnets D^4 and E^4 for the reason that if they were left in bridge when the battery is connected across the line, they would operate simultaneously, and by making contact at the point α would close the release circuits of the releasing magnet J^2 and of the back release relay J' , whereupon the entire connection would be broken down. To prevent this, we put in the cut-off relay V . The relays V and V' are constructed so as to have the same electrical characteristics. However, relay V' is equipped with a set of springs which make contact when the relay is energized, whereas the springs of relay V serve to break contact when it is energized. Consequently, if these relays are simultaneously energized, the springs controlled by the armatures of the relays will affect their operation in such a manner that the springs of relay V will break before the springs of relay V' make. Conversely, when the relays are simultaneously deenergized, their respective spring combinations will affect the relay operation so that the springs of relay V' will break before the springs of relay V will make. Therefore, the springs 57, 58 and 59 of relay V are separated, and the connections of the relays D^4 and E^4 are broken before the magnets X and Y and the main battery are bridged across the wires 15—16. In practice it might be difficult to obtain relays of like electrical characteristics. However, notwithstanding this fact, and assuming that the relay V' might close its contacts before the relay V opens its contacts, the time interval during which the contacts of relays V' and V are both closed will be of such short duration that a relay or electromagnet included in such circuit will not receive sufficient current for its operation. Obviously if such a condition should arise, it could be readily overcome by making relay V' slightly slow to pull up and to release.

When these relays X and Y are connected, X to the wire 15 and Y to the wire 16, they serve thereafter to control the release circuit, as will be pointed out in the statement of operation.

The magnets X and Y , like the magnets V and V' are designed with like electrical characteristics and control respectively a break and a make contact. These two relays function exactly the same as relays V and V' , and obviously relay Y could also be made slightly slow to pull up and release. Therefore, when these relays are simultaneously energized, the contact of X will open before the contact of Y closes, and conversely when the magnets are deenergized, the contact of Y will open before the contact of X closes. The release circuit controlled by these relays

requires the simultaneous closing of the contacts of magnets X and Y . If the calling subscriber hangs up his receiver before the called party does, the subscriber's loop will be opened at the calling party's station, and this will open the circuit containing the magnets X and Y which will therefore be deenergized. However, as the subscriber momentarily grounds both sides of the line directly after the subscriber's loop is opened, the relay Y , which is connected from battery to the rotary side of the line, will be momentarily energized and again close its contact. Therefore, as relay X is deenergized and relay Y momentarily energized, the release circuit will be momentarily closed and release the switches. This circuit will be described in detail hereinafter.

We will now refer to Figure 1^a, and will describe the repeating trunk circuit therein shown. The underlying principle of this circuit is that in trunking calls the proper place for the trunk line insertion is before the point of selection of the highest number in any exchange. As will appear from the statement of operation, the first selectors pick out idle trunk lines leading to the second selectors, simultaneously selecting the thousands number. In an exchange above ten thousand there would be another set of selectors ahead of the second selectors, of course, but the trunk is inserted after the first selector always. At this point difficulties are experienced in practice in transmitting the impulses over the trunk line with rapidity and certainty, and this difficulty is heightened by the necessity for the insertion of condensers in the trunks; for then repeaters are used, but the condenser discharge blurs the repeated impulses to a very marked degree. We have found a means to obviate this, and at the same time to provide for certain other requirements in connection with the registering and the control of pay stations. In putting a call through, where it is to be registered at the calling end, as already noted, we have provided a polarized relay L (see Figure 1), which does not respond to the ordinary signaling current to register, but when reversed current is thrown back on the line it does respond to indicate that a call has been completed. In order to secure this operation upon the completion of the connection, it will be understood that all that is required is to make the connections from the main battery to the cut-on side of the connector circuit (see Figure 3) such that current will flow in the proper direction to register when cut back. Here we wish to call attention to the fact that while we have shown but one battery, we are not limited to one battery, and in fact, in practice, especially where reversals of current are required, as in trunking, or in differen-

tial registering, several batteries may be employed.

The trunk circuit shown in Fig. 1^a will now be described with special reference to the automatic system herein shown, but it will be understood that its use is not limited to this specific system and that it is applicable to any system of signaling in which repeating is required.

In Figure 1^a, which is supposed to be interpolated between Figure 1 and Figure 2, we have shown the multiple contacts m' in the banks of the first selectors, connected by the trunk wires 13—14' and 14—13' to a second selector, which may or may not be in the same exchange as the first. Each side of the trunk is conductively divided but inductively made continuous by the condensers C². The wire 13—14' continues as the vertical side of line, while the wire 14—13' continues the rotary side. Impulses coming over the vertical side for the second selector cannot pass the condenser C² directly, but must be repeated, and the same with the other side of line. We therefore provide the repeater Z, having its magnet z connected to the wire 14 by the wire 90, and thence by wire 91 through cut-off contacts 92, 93 and 94 to the battery B³. Similarly the magnet z' is connected by wire 95 to wire 13 and thence by wire 96, through contacts 93 and 94 to the battery B³. The contacts 92, 93 and 94 are normally closed, but adapted to be opened by magnet Z⁵, which is in a branch circuit 97—98 extending from the battery B³ to two magnets Z' and Z² by branches 99 and 100, and thence to the respective contacts 101 and 102 of the oppositely polarized relays Z³ and Z⁴. These relays are in series in the circuit 103, which terminates in the two contacts 104 and 105 lying on opposite sides of the ground contact 108. The armature z^2 of the magnet z controls the long spring 106, and the armature z^3 of the magnet z' controls the long spring 107, and these two armatures also control the springs 104 and 105. When either magnet is energized, it grounds its spring 104 or 105, and when both are energized together they close the contacts 106 and 107 together.

The magnets Z' and Z² respectively control the armatures 109 and 110, which in turn control the continuity of the branch circuits 111 and 112 with the back supply circuit 113. Each of these branches has a battery connection, and these battery connections are relatively reversed, as shown by the batteries B' and B². Adapted to be bridged across the circuit 13—14 with one or the other of the batteries B' or B², through the circuit 113 and the ground return 114, are the two magnets Z⁶ and Z⁷, controlling the first a front contact 115 and the second a back contact 116. When both

magnets are attracted, one contact is open, and the armatures are connected in series at 117. These armatures and these contacts jointly control the continuity of the branch 118 of the trunk release circuit 119 leading from the battery B³ to the back release contacts m^2 . A parallel branch 120 is controlled by the two springs 106—107.

Impulses over the wire 13 affect the magnet z , which repeats into the wire 13' by grounding its contact 105, and thereby grounding the said wire 13' through the branch 123. Similarly, impulses over the wire 14 affect the magnet z , which repeats into the wire 14' by grounding its contact 104 and thereby completing the branch 121. Ordinarily the repetition would be straight from wire 13 into wire 14', and from 14 into 13', but when such is the case the impulses repeated are blurred or somewhat smoothed out, particularly when transmitted at high speed, by the discharge of the condenser. We avoid this by transposing the wires at 125 so that the condenser discharge in each case is into the opposite wire from that into which the repetition goes. The repetition and battery currents therefore go straight through, while the talking circuit is transposed, but obviously the latter makes no difference. We have shown several transpositions, but these are not necessary always, and in fact, when we speak of a transposition at 125, the term is merely relative, as we mean by this only the connection of the wires 121 and 123 for repeating, to opposite sides from those inductively connected through the condensers to the sides in which the respective impulses originate.

In this Figure 1^a therefore, there are shown two principal features of invention, both of which, together with others, we shall claim broadly. The first is the transposition for rapid repeating forwardly, and the second is the control of the batteries B' and B² so that when current of one direction or the other is cut back over the metallic talking circuit from the connector cut on relay V', or in any other way, the repeated current sent back will be automatically controlled through the trunk as to its polarity. This is important in the registering, pay station, and other work which we have mentioned as requiring polarity control.

The operation of our system, apparatus and methods will have been largely understood from the preceding description; but we will here briefly review the same.

Taking the system shown in Figures 1, 2, 3 and 4, we will first assume a call originating over the line 1—2 from the station A (number 12) and intended for station A⁴ in Figure 4. Subscriber A first takes down his receiver, R, and turns his impulse transmitter (not shown) so that after the rising of the hook a ground circuit will be completed from 130

G through the resistance r and contacts a^2-a to the vertical side of line 1, current flowing out over this path from the battery B through wire 32, contacts k', k^2, k^3 , wire 5 31, relay D and line wire 11. The first number of impulses sent we will say is one, assuming the number of station A⁴ to be 1920. Relay D controls magnet D' to step up the spindle v until the wiper v' registers with 10 contact m' in the first row of second selector contacts in the bank. As the impulse transmitter at station A comes to rest, it momentarily closes together the contacts $a'-a^2$, which sends one impulse out from battery B 15 through wire 32, springs $k'-k^2$, wire 33 and magnet E over wire 34, side switch wiper f^2 to wire 12, to the substation and to ground. Magnet E attracts its armature and closes spring e on the ground contact g , thus completing 20 circuit through the private magnet P, which opens the circuit 37-38 of the vertical magnet, and stops any further vertical movement of the spindle. It also lets the side switch F step around one contact. In 25 doing so, the arm f^0 passes onto contact f^{10} and so cuts in the magnet E', which immediately takes current through the wire 39, and battery wire 32, vibrating continuously until cut out. This vibration is produced 30 by the armature separating contacts when attracted, this being represented in the diagram throughout by a pair of points normally touching each other between the magnet coils and adapted to be separated by an insulating 35 point on the armature. The armature also rotates the spindle v so that the wiper v' passes from one pair of multiple contacts to another, touching one before it leaves the last one, and continuing around until it reaches an idle pair, which means an idle 40 second selector, which again means a selector without any ground on the wire 49. By making the wiper bridge the contacts without a break between them it passes over those 45 that are busy because the busy ones, being grounded through the wire 49, hold up the magnet P by current over the following path: Battery B, 32, P, 390, 40, $f^{10}, f^3, J, 52, v^2, m^2, 49$, and ground. The instant an idle selector contact is reached this grounded circuit is broken, and the magnet P lets go its armature, with the result that the side switch F is released for the second step, the rotary magnet E' is cut off and the arm f is open, 50 the arms f' and f^2 each pass on to its third contact f^{20} , completing the talking circuit and disconnecting the controlling relays and magnets therefrom, while the arm f^3 passes on to its third contact and closes the ground 55 60 by wire 54 to the wire 53 through magnet J and wire 52 to the contact wiper v^2 , contact m^2 and wire 49, this being utilized later on in restoring the apparatus, as will be noted hereafter.

65 We now have the station A connected through to the second selector circuit. The calling subscriber again turns his transmitter plate to send nine impulses, by closing the contacts $a-a^2$ together nine times and afterwards the contacts $a'-a^2$ together once 70 as before. The nine impulses cause the vertical relay D² to be energized nine times over a circuit from battery, wire 32, through the magnet D², wire 45 and wire 13, back through wire 11 to the substation. The magnet D² attracts its armature nine times to ground the spring d^2 , thereby closing the circuit of the vertical magnet D² nine times, which steps up the spindle v of the second selector nine rows to the row of the nine 75 hundreds in the connector contacts m^3 . The single impulse that follows over the rotary wires 12 and 14 passes through the relay E², which grounds the spring e^2 and thereby closes circuit from battery, wire 32, through the private magnet P², the latter opening the vertical magnet circuit D³, and permitting the side switch F' to move all its arms f^4, f^5, f^6 and f^7 around one step, the arm f^4 cutting in the rotary magnet E³, and the arm f^7 connecting the wiper v^4 back through the magnet J' and P² to the battery wire 32. The rotary magnet, being in circuit, commences to vibrate and step around the spindle v as before, until the wiper v^3 and wiper v^4 find contacts of connectors that are idle, or, in other words, ungrounded. In this connection we should call attention to the fact that the instant the spindle v in Fig. 1 (first selector commenced to rise, it released 80 a spring u (see the left-hand side of the figure) of a switch U, breaking circuit with contact u' of the bridging cut-off relay K, and grounding the wire 35 on the contact u^2 . This completed a circuit from ground as follows: G, $u^2, u, 35, o', o, 36$, and to all the contacts m^{10}, m^{12}, m^{14} , and m^{16} in the multiple banks of connectors upon which connection might be made with the line 1-2. These private bank contacts all being 85 grounded, will test busy, therefore, if anyone else attempts to break in by calling line 1-2 or any of its stations. Similarly, the instant connection was made between the first selector and the second selector at v^2, m^2 , the side switch arm f^2 moved into its third position, connecting ground to the wire 54, and so through wire 53, magnet J, and wire 52 to the wiper v^2 , and thence to all the connected multiple contacts m^2 of the second 90 selector shown, wherever they might be distributed, so that no first selector could get in on that second selector while thus in use.

95 As soon as the second selector finds a connector that is idle, the ground circuit through magnet P² (Fig. 2) is broken, the side switch F' makes its last step, the arms f^5 and f^6 complete the metallic circuit 13-14 onto 15-16, the arm f^4 cuts off the rotary 100 105 110 115 120 125 130

magnet, and thereafter remains open, and the arm f^7 closes the ground of contact f^{20} onto the magnet J' , and so to the wiper v^4 , which, being on the contact m^4 , makes it and 5 its connected multiple contacts of the connector thus selected test busy thereafter during the connection.

The circuit has now been traced to the connector shown in Figure 3, with a clean metallic circuit made up of wires 1, 11, 13, 15, on one side, and 2, 12, 14, 16, on the other side. This is the connector, which actually selects the contact of the line wanted. We find the side switch F^2 present in this case also, and 15 that it controls the circuits of three magnets, the vertical magnet D^5 , the rotary magnet E^5 , and the ringing relay W .

The subscriber now sends the number 2, which causes two impulses to pass along the 20 wires 15, 13, 11 and 1 and to ground at station A, through the connector circuit as follows: Battery B to spring 59, to springs 58 and 57, wire 56, relay D^4 and wire 55 to wire 15. This vertical relay D^4 is thus energized 25 and it in turn closes a circuit containing magnet D^5 which then steps up the spindle v until its wipers v^5 and v^6 reach their respective second rows of subscribers' contacts. The single impulse over the rotary side 16 30 of the line from the battery B by wire 32, springs 59—58, wire 61, springs 62—63, wire 60, to relay E^4 , wire 16, and back to the subscriber's station operates magnet E^4 which grounds the spring e^4 , closing the circuit of 35 the private relay P^3 . In moving its armature, the magnet P^3 lets the side switch go around one contact, cutting in the rotary magnet E^5 , and connecting the wiper v^6 through the arm f^{70} and contact f^{10} , to the 40 spring p^3 to prepare a circuit to release the connector if the desired line is found to be busy. The subscriber now sends the number 0, which is ten impulses over the vertical side of the line. This again works the vertical 45 relay D^4 as before, which grounds the spring d^4 and this time closes the circuit 64, 65, 68, 67, 32, B, of the rotary magnet E^5 . This brings the wipers v^5 and v^6 onto the individual contacts m^5 and m^6 in the multiple 50 bank of the connector S^2 in Fig. 4. The consequent grounding of the rotary side of the line at the substation will operate relay E^4 . The operation of relay E^4 will close the circuit containing magnet P^3 and the operation 55 of the latter will close a contact at springs p^3 and p^4 . Now, if the called line is busy, the contact m^6 will be connected to ground, as a result either of the operation of switch U (Fig. 4), or, due to the ground circuit, to 60 wiper v^6 by way of side switch arm f^{70} of the switch used in the set-up connection. Therefore, when the magnet P^3 is operated and the wiper v^6 is connected to busy line, a circuit 65 will be completed from ground by way of wiper v^6 , arm f^{70} , springs p^3 and p^4 , relay J^2 ,

and wire 32, to battery. This will operate the relay J^2 which, in attracting its armature, releases the stop pawls which retain the spindle v in its rotated and elevated position, and thus the switch is restored to normal. 70

The operation of the magnet P^3 does not affect the side switch F^2 , and as the connector switch is released as soon as the magnet P^3 is operated when the called line is busy, the side switch F^2 is likewise released and cannot pass out of its normal position when the magnet P^3 is deenergized. 75

The calling subscriber will next operate his ringing button. This will close a circuit 80 containing the vertical relay D^4 over a path to ground, from the subscriber's station (Fig. 1), through resistance r , contacts a^4 , a^3 , a^{13} , a^{14} , a^6 and a^5 to wire 25, and thence by wires 3, 11, 13 and 15 to the vertical relay 85 D^4 , wire 56, springs 57, 58 and 59, wire 32 to battery. The operation of the vertical relay D^4 will close the circuit of the vertical magnet D^5 , which in turn will raise the spindle v one step. As soon as the switch takes its 90 first vertical step from normal, springs 101' and 102' of the off-normal switch close and thereby complete a circuit from ground to the secondary busy-back transformer, springs 101 and 102 and side switch arm f^{60} to the 95 rotary side of the line, and thence out to the substation and back on the vertical side of the line and through relay D^4 , to battery. This gives the calling subscriber the busy tone. The calling subscriber will then hang 100 up his receiver and will therefore momentarily ground both sides of the line which will simultaneously operate relays D^4 and E^4 . These close their contact springs d^3 — e^3 at point x , whereby the following circuit is 105 completed: Battery B, wire 32, J^2 , e^3 , d^3 to contacts m^4 , wiper v^4 , magnet J' , arm f^7 , contact f^{20} and ground. The magnets J' and J^2 both act, the latter to restore the connector S^2 and the former to close the circuit B, 32, 110 50, I' , 51, 49, m^2 , v^2 , 52, J , 53, arm f^3 , contact f^{20} , 54, and ground. Whereupon the magnet I' pulls out the pawls that hold the spindle v of the second selector S' (Fig. 2), 115 and restores this to zero; while the relay J closes the circuit of the release magnet I as follows: Battery B, 32, 42, I , 41, j^2 , j' , and to ground. Whereupon magnet I pulls out the pawls from the spindle v of the first selector (Fig. 1), S , and permits that to go to zero. The magnet I , magnet I' and magnet J^2 in each case, when releasing the pawls 120 from the vertical spindle also pulls over the side switch F , F' or F^2 to the normal or zero position shown in the figures. When the spindle v of the first selector S drops down, it takes the ground off the wire 35 by pushing down the spring u of the switch U . Thus all parts are again normal and all 125 switches idle. 130

Suppose, however, that the line wanted does not test busy. The subscriber, after sending in his last number presses his ringing button which closes a contact at the 5 springs a^{13} and a^{14} to ground the vertical side of line as follows: G, r, springs a^3-a^4 , a^{13} , a^{14} , a^6 , a^5 and by wire 25 to the vertical side of line. This permits current to pass back from battery, wire 32 in Figure 3, 10 through vertical relay D⁴ to the subscriber's station and ground. The spring d^4 is again grounded, and a circuit is completed from ground, through springs p^2-p' and wire 65 to arm f^{20} , contact f^{20} , wire 69, the ringing 15 relay W and battery. This relay attracts its armature and throws down the springs thereof, opening the vertical side of line 15' entirely. It also opens the rotary side of line 16' and connects the forward end 20 thereof through its terminal 71' to the ringing generator wire 170. Current then passes out through wire 16', lower contact m^5 , wire 18, wire 20, ringer Q' and to ground through the condenser at the wanted station A⁴.

After ringing, the calling subscriber A releases his calling button, the vertical relay and the ringing relay in Figure 3 let go, and the metallic talking circuit is clear 30 through from one station to the other, as marked in heavy lines, except for the interposed condensers C'. All magnets and relays are disconnected, and all grounds are off, except that the magnets D⁴ and E⁴ are 35 connected from the vertical and rotary side of the line, respectively, to the springs of the cut-off relay V, and these springs in turn are connected to the battery B; whereas the magnets V and V' are connected in series 40 with the battery B, this circuit being bridged across the wires 15'-16' leading to the called subscriber's station A⁴. The latter bridged connection is adapted to give current to the subscriber A⁴ in Figure 4 45 over his metallic circuit; but it should be particularly noted that there is no bridged talking battery on the metallic circuit back to the calling subscriber.

The called subscriber A⁴ we will suppose 50 now answers by taking down his receiver. His switchhook thereupon rises and closes his metallic talking circuit, whereupon current flows from the bridged battery through the two magnets V-V' out to the station 55 A⁴ and back. Both magnets attract their armatures, but the springs of relay V break contact before the springs of relay V' make contact, and thereby cut off the vertical and rotary relays D⁴ and E⁴, before the magnets 60 X and Y are cut on, with their bridged battery connections. If it were not for this cut-off there would be a short-circuit through the relays D⁴-E⁴, which were bridged, and they would work the release

mechanism by closing their contacts d^3-e^3 65 at the point x.

When the magnet V' acts, it cuts on the relays X and Y and bridges the main battery across the connector wires 15-16, so that talking current now flows back through 70 the metallic circuit to the calling station A. Subscriber A thus gets current for his telephone transmitter T.

Both magnets X and Y now hold up their armatures during the connection, and 75 it is to be observed that this keeps the release circuits of the back release relays open, because the contacts $x'-x^2$ of the magnet X are open, although the others $y-y'$ are closed. The relays D⁴ and E⁴ being cut out, 80 their release contacts are open at x.

At the conclusion of the conversation, when subscriber A hangs up, he breaks the metallic circuit and momentarily grounds both sides thereof by closing together the 85 springs a^{10} , a^{11} , a^{12} . The opening of the subscriber's loop deenergizes the relays X and Y, and the subsequent momentary grounding of both sides of the line momentarily energizes relay Y, as previously explained. This closes a circuit from the ground on side switch contact f^{20} , by way of side switch arm f^7 and relay J' to wiper contact v^4 and contact m^4 , and thence by

way of wire 700, contacts x^2 and x' , wire 95 70, contact y and y' to release magnet J², and by way of wires 750 and 32 to battery. The release magnet J² will thus be energized, and in drawing up its armature it pulls out the retaining pawl of the spindle 100 v of the connector. Fig. 4, restoring this switch to normal. The relay J', Fig. 2, closes the local circuit of the release magnet I' of the second selector through wire 49, and the back release relay J of the first 105 selector, which in turn closes the local release circuit of release magnet I of the first selector. The operation of the release magnets associated with the various switches will restore all of these switches to normal. 110

If the subscriber A⁴ hangs up his receiver first, the magnets V and V' will be deenergized. The magnet V' will be momentarily reenergized, however, when both sides of the lines are momentarily grounded. 115 This will close the release circuit through relay J' and J² hereinbefore described, and the various switches will be restored to normal in a manner similar to that described when the subscriber A is the first to hang up his receiver.

We have thus described the operation of our common battery system for a complete call, cutting back the talking battery to the calling subscriber when the called subscriber 125 answers, together with the various effects on the relays and magnets of toll boxes or registers. It remains to describe the oper-

ation of our trunking apparatus, and the method of selecting party line subscribers, of enabling one party line subscriber to signal any other station or his own station on the party line, as well as to get in on his own line without finding it busy, if he himself is calling, the operation of subsidiary apparatus thereby, etc.

Referring to Figure 1^a the trunk line we show is adapted to form an extension from a given first selector in one exchange to a group of second selectors in the same or a different exchange. In Figure 2 will be found a line marked "line of trunk connection." The ends of the two wires 13' and 14' in Figure 1^a are supposed to be connected directly to the wires 13-14, where they are cut by this line, the wire 49 in Figure 2 being the same as wire 49' in Figure 1^a. Considering the trunk line to be interpolated between the first and second selectors therefore, and having the trunk broken by the condensers C², the operation is as follows:

The transmission of impulses and selection of an idle trunk through its contacts m' m², is the same as before, the first selector then connecting the subscriber's line through on to the trunk, just as heretofore we have described it as connecting onto the the second selector circuit direct. The second set of impulses coming along over the vertical wire 13 cannot pass on into the second selector circuit direct because of the condenser. Their circuit is from the battery B³, through the springs 94, 93, and by wire 96 to magnet Z', wire 95 to wire 13, and so back to the subscriber's station and ground. The magnet z' when energized grounds the contact 105 by forcing it against the contact 108, and thereby grounds the wire 13' by the following path: 13', 124, 123, 105, 108, to ground. For each impulse, current will then flow back from the battery B, Figure 2 through the vertical relay D², through wire 45, wire 13, wire 13', (Figure 1^a), and so to ground as stated. The operation of the mechanism in the second selector circuit is the same as already described.

The single impulse that comes over the rotary side 14 travels through the circuit B³, 94, 93, 92, 91, z, 90, 14, and back to the calling subscriber's station. The magnet z grounds the contact 104 at 108, grounding the wire 14' through wire 121.

It will be observed that each impulse that comes over the wire one way or the other means the charging of the line and the charging of the condensers, with a subsequent discharge. According to our arrangement, however, an impulse over wire 13 would affect magnet z' and repeat into the wire 13', while the condenser C² discharges across into the wire 14', which is not re-

ceiving impulses at the same time, and hence cannot be disturbed. Similarly, the discharge from the condenser of wire 14 is into the wire 13'. The transmission of all subsequent impulses to the selectors and connector is the same. This brings us to the next step, which is the cutting back of battery of the proper polarity when the called subscriber answers. It will be remembered that the direction of current flow which goes back to the calling subscriber's station is determined by the direction in which the battery B is connected across the circuit 15-16 by the cut-on relay V' in Figure 3. Flow of current from this battery cannot go all the way back to the calling subscriber's station, however, because of the condensers, not to mention the drop that would result from the resistance of a long trunk if there were no condensers. We will suppose the connection to have been completed, and the called subscriber to have answered. His answering energizes the relays V', V, which cut on the battery B across wires 15-16 and send current back through the wires 13-14, and from the latter through 14', 121, 104, contact 130, bridge wire 103, through the two polarized relays Z³ and Z⁴ in series, back to contact 131, spring 105, wire 123, and wire 13' to the wire 13 and back to battery.

The direction in which the battery B is connected across the circuit in Figure 3 determines which of the relays Z³-Z⁴ will attract its armature, for these are oppositely polarized. Supposing it to be Z³, this closes the local circuit 101, 99, Z', 98, Z⁵, 97, battery B³, and ground. Magnet Z⁵ opens the circuit of the repeater magnets z and z' at the springs 92-93-94, this being necessary to avoid the attraction of their armatures with consequent interference. At the same time the magnet Z' closes the circuit 114, B', 111, 109, 113, Z⁶, wire 14, back to the calling subscriber's station, out again, wire 13, magnet Z⁷, wire 114', and ground back to the battery B'. In other words, battery B' is bridged across the wires 13-14 in the same direction as the original battery in the connector circuit, Figure 3. Suppose that battery to have been reversed, then the polarized relay Z⁴ would have attracted its armature and connected the reversed battery B² to send back current. Thus, the direction of the current supplied to the calling subscriber is controlled through the repeater. If the trunk line is very long, several of these repeater circuits may be used to off-set the excessive trunk line resistance. The calling subscriber, even if working over a long distance line, therefore, would get back current of the proper direction.

This brings us to the question of releasing, which is the last step to be considered. The magnets z and z' on the calling end of the

trunk when they both attract their armatures close the contacts 106 and 107 together, thereby closing the branch 120 of the release circuit traced as follows: battery B^3 , wire 5 119, 120, 107, 106, 120, 119 and contact m^2 in the multiple bank m of the first selector, Figure 1, thence in Figure 1 by the wire 52 through magnet J and to ground. Relay J works the release magnet I to return the first 10 selector to zero. The simultaneous attraction of the armature of relays z and z' will likewise simultaneously ground the two sides 13' and 14' of the trunk circuit by means of their springs 104 and 105. This 15 will cause the restoration to normal of all of the rest of the switches used in setting up the connection. This is the release that would occur if the subscriber A hung up without completing the connection. After the 20 called subscriber has answered, however, one of the batteries B' or B^2 is cut back and bridged across the calling end 13—14, and at the same time the magnet Z^5 opens the contact at springs 92—93—94 and cuts off the 25 two magnets z and z' . The bridge through these magnets is opened to prevent their operation by the bridged battery and a consequent premature release of the switches. Some means must therefore be provided for 30 breaking the connection and restoring the first selector in case subscriber A hangs up first. Of course, if the called subscriber hangs up first the magnets z and z' would again be cut in and then, when the calling 35 subscriber hung up, they would act as we have stated to clear out. The magnets Z^6 and Z^7 serve to control the release of the first selector switch from the calling subscriber's end when the called subscriber has 40 his receiver off the hook. When the calling subscriber hangs up his receiver before the called subscriber does, he opens at the subscriber's station the circuit containing the magnets Z^6 and Z^7 , which will therefore be 45 deenergized. However, the subsequent momentary grounding of both sides of the line will reenergize magnet Z^6 . This closes the release circuit from ground (Fig. 1), wire 54, side switch contact f^{20} , side switch arm f^3 50 and relay J to wiper v^2 and contact m^2 (Fig. 19), wire 119, contact 115 and armature of relay Z^6 , armature and contact of relay Z^7 , wires 118 and 119 to battery B^3 . Thus relay J will be energized. The actuation of 55 relay J will cause the operation of release magnet I which will restore the first selector switch.

We shall now briefly state the operation where a subscriber on one line calls another 60 subscriber who is on a party line. The first steps through the first selector to the second selector are the same as the plain connection we have heretofore followed. Then begins a divergence. We will assume there are four 65 parties on the line, as shown in Fig. 1. It

will be remembered that all the connectors such as shown in Fig. 3 are divided into groups, each group having multiplied to its respective banks m the subscribers' wires 17—18 whose numbers are comprised within 70 the same hundred. Thus there would be one group of connectors in which there are contacts for subscribers from 1 to 100, another group for subscribers from 101 to 200, another from 201 to 300, another from 301 75 to 400, and so on. The second selectors are similarly divided into groups with regard to the thousands. In other words, there would be one group of second selectors containing contacts of all the connectors from 80 100 to 900, another group for those from 1000 to 1900, and so on. As heretofore traced, in order to select such a number as for instance 1920, the calling subscriber would put himself onto an idle second selector in the second thousands group, then through that onto an idle connector in the ninth hundred group thereof, then through that onto its number 20 line contact. Now 85 for party line service, of course, each line 90 is a unit for calling in, having but one first selector switch, or in a manual exchange one answering jack. But for the purpose of being called, we regard each subscriber on the party line as a separate unit, and give him 95 a separate line terminal, corresponding to a multiple jack. The four subscribers on the one line have their four calling terminals (or multiple jacks) in four different connector groups, which is the same as to say 100 that each subscriber has a different hundreds number from the others. Now, in the present case we have assumed the four subscribers A , A' , A^2 and A^3 to be numbered 105 12, 112, 212 and 312, respectively. The multiple or calling terminals of subscriber A are therefore found only in the first hundred bank or group of connectors, as indicated in m^9 — m^{10} in Fig. 1. Subscriber A' has his 110 multiple connecting terminals in the second hundred group at m^{11} — m^{12} . Subscriber A^2 has his multiple connecting terminals in the third hundred group at m^{13} — m^{14} . And subscriber A^3 has his terminals in the fourth hundred group at m^{15} — m^{16} . But, it will be 115 remembered that the ringing generator or generators are connected in the connector groups. We can therefore give a different kind of ringing current, or a different path 120 for ringing current to each separate hundreds group. Thus to the connectors in the first hundred group we preferably give a generator furnishing say 20 cycle alternating current; to those in the second hundreds group a generator giving current at 40 125 cycles; to the third hundreds group 60 cycle current; and to the fourth hundreds group 80 cycle current. The result is that in order to call subscriber A , a calling subscriber connects himself or is connected to the first 130

hundreds group of connectors, because A's number is 12. This group of connectors is supplied with 20 cycle current only. Hence, in ringing, 20 cycle current goes over the line 1-2, and as A's ringer only, on that line, is adjusted to respond to that particular current, his bell will sound to the exclusion of others.

Similarly, in calling A², the calling subscriber would go through the third group of connectors, because A²'s number is 212. This group of connectors has 60 cycle current only. Hence, the bell at station A² only will ring.

We have described the use of ringing current of different frequencies, but we wish it clearly understood that we are not limited to this. We may use any of the devices known in the art for selective ringing. For example, the bell at station A may be polarized for plus current, and be wired in a ground tap from No. 2 side of line. Bell at station A' may be polarized for minus current, and be wired in a ground tap from the same side of line. Bell at station A² may be polarized for plus current, and the bell at station A³ for minus current, and these may be wired in ground taps from the No. 1 side of the line. To select one or the other station the connectors of the different groups would be arranged to place positive or negative pulsating current to one side or the other of the line as desired, according to the group. Step-by-step selectors may also be used, by providing each group of connectors with a make-and-break device sending a distinctive number of impulses.

So much for the connection of a party on one line through another line to one of several subscribers thereon. More difficult is the problem of how to permit a subscriber to select and call another on his own line. As we have shown, the moment a first selector switch starts it puts a ground on the private line or busy terminals m¹⁰, m¹², etc., at the switch U. The first supposition would be therefore that when one party on a party line called in he would start the selector, go through the second selector and connector to the hundred group of the wanted subscriber on his own line, and by the time he got there would find it busy, owing to the condition of his own switch. To remedy this is the function of the differential relay O in Figure 1. This relay is differentially wound and is copper jacketed; therefore, when current flows in the metallic circuit, this relay will not be energized, whereas, for current in one side of the line only, the magnet will lift its armature o off the contact o', and thus disconnect the ground at switch U from the private line contacts m¹⁰, m¹², etc. This private bank circuit is normally as follows:

Ground, u², u, 35, o', 36 and to the private bank contacts. The contacts o—o', are closed at all times except just at the instant that impulses are being sent over one side for selecting, which is usually one second or less of time. During this very brief interval the line would not test busy, and some one else might get in, but this is almost impossible in practice.

Suppose now that A calls A'. He starts the first selector S, the second selector S' and the connector S² in the second hundreds group. The connector steps up its wiper v⁵ to the second row of contacts m¹¹, and then steps around one to the second contact in the row. The impulse that produces this step is going through the vertical side of the line, 11, and raises the armature o for the briefest fraction of a second, just as the wiper v⁵ comes on the proper contact. It stops there, and the busy test circuit is closed again. As a matter of fact the armature o, if made properly, will respond to each impulse, and therefore the busy circuit is never open at one time for longer than perhaps one-tenth or less of a second. Thus, the subscriber comes in on his own line. As yet there is no flow of current in his metallic circuit for talking, this being controlled by the called subscriber back through the connector relay V'. The group of connectors he has selected automatically give 40 cycle current, and ring the bell at station A'. When A' answers by taking down his receiver, talking current is cut back over the calling end.

For a party line system, in which the subscribers' ringers are bridged from either side of the line to ground, special provisions must be made for the actuation of the ringers tapped from the vertical side of the line. The resistance r at the subscriber's station is used for this purpose. It will be evident, if there were no resistance in the circuit to ground, that the subscriber, upon depressing his ringing button, would put a short circuit to ground on the vertical side of the line. This shunt would rob the ringers of the necessary current required for their operation. The resistance r is therefore made high enough to prevent the shunting of the major portion of the ringing current which will therefore seek a path through the desired subscriber's ringer. The resistance r at the subscriber's station is further useful in preventing a premature disconnect on a party line connection. Thus, this resistance r prevents a premature release by a subscriber on a party line, who cuts in on a connection which had been previously established with another subscriber on the same party line or some other line. It will be evident that if a connection with a party line subscriber had been established, that a second party on the party line,

upon cutting in on the connection and hanging up his receiver, would momentarily ground both sides of the line. Therefore, if the resistance r were not included in the 5 ground tap at the subscriber's station, both sides of the line would obtain a momentary connection direct to ground. This direct ground tap to the vertical side of the line would shunt out the relay X at the connector 10 circuit, and the deenergization of this relay would close the release circuit and restore the switches to normal, as previously described. However, when the ground tap at the subscriber is wired through the resistance r , the relay X is connected to 15 ground in parallel with the resistance r , and in this instance sufficient current will flow through the relay X to maintain it in its operative position, and thereby prevent 20 the premature disconnect.

Although we have specified a line between the first and second selectors as the line for trunk connection, we have shown another place in Figure 3, marked "trunk connection," where extended trunks such as 25 shown in Figure 1^a may be inserted. Similarly, they may of course be inserted at a corresponding point in the first selector circuit of Figure 4. Our invention is not 30 limited to any particular location of the trunks.

We are fully aware that many changes 35 may be made in matters of detail, and even in some broad features of the system and apparatus described herein, without sacrificing or departing from some or all of the features and principles of our invention. Thus, the central-energy current supply system may be divorced from the party line 40 scheme. By simply omitting the common battery features, particularly in the connector circuit, and supplying local batteries at the subscribers' stations for talking, the party line features may be used with perfect 45 success in any existing Strowger automatic system. Similarly, the central battery scheme can obviously be used with other circuits, and without party lines. It must be understood that all such changes 50 lie entirely within the scope and purview of our invention.

What is claimed is:

1. In a telephone system, automatic switching apparatus normally at rest for 55 extending a connection from a calling to a called line, means whereby talking current is supplied through only two relay windings to the substation of the calling subscriber, and whereby the same kind of current is also supplied through only two relay windings to the substation of the called subscriber, none of said relays being individual to the called subscriber.

2. A telephone system comprising a line 60 circuit, a transmitter in said circuit, a source

of talking current, a condenser in each side of said circuit, bridging relays distributed along the said circuit, switching means controlled by said relays, means for cutting off all except a single pair of relays at each 70 side of said condensers, and means for supplying current only through the said remaining four relays to the said circuit for talking purposes.

3. A telephone system comprising a line 75 circuit, a transmitter in said circuit, a source of talking current, a condenser in each side of said circuit, bridging relays distributed along said circuit, switching means controlled by said relays, means for 80 cutting off all except a pair of relay windings on each side of said condensers, and means for supplying current only through the remaining four windings to said circuit for talking purposes. 85

4. A telephone system including a calling and a called subscriber's line provided with terminal contacts, an automatic connector switch, automatic means for connecting the terminal contacts of the calling line to 90 said connector switch, subscriber controlled means for then operating said automatic connector switch to extend the call to the terminal contacts of the called subscriber's line, a release magnet for returning said connector switch to normal, and a plurality of relays for said connector switch adapted to remain energized while the connector is in use to prevent the operation of said release magnet. 100

5. A telephone system including a calling subscriber's line and a called subscriber's line, a group of connector switches having access to said called subscriber's line, an automatic progressively movable selector 105 switch under the control of the calling subscriber for selecting an idle one of said connector switches, means for operating said connector switch to extend the call to the called subscriber's line, release means for 110 said connector switch, and a plurality of relays for said connector switch that remain energized while the connector is in use to prevent an operation of said release means.

6. A telephone system including subscribers' telephone lines divided into groups, automatic progressively movable connector switches likewise divided into groups corresponding to the groups of subscribers' lines, automatic trunking means divided 120 into groups and individual to the subscribers' line groups, subscriber controlled means for actuating said automatic trunking means whereby substantially simultaneous connections may be extended from the calling subscribers' lines of one group to connector switches in another or the same group, and relays for each of said connector switches, a plurality of the relays of any one connector switch being adapted to re- 125 130

main energized during connection for preventing the release of the automatic trunking means and the said connector switch used in establishing a connection.

- 5 7. A telephone system comprising calling and called lines, a two-strand link circuit and automatic switches for connecting the ends of said circuit with said lines to complete a conversational circuit between them, 10 condensers in the strands of said link circuit, a pair of relays connected in bridge of said strands on each side of said condensers, release magnets for said switches, a release circuit including said release magnets and 15 contacts of a pair of said relays, and a release circuit for the release magnet of one of said switches including contacts of the other pair of said relays.
8. A connector for automatic exchanges 20 including a pair of talking conductors, a condenser connected in each said conductor, a central source of current connected to one of said conductors on opposite sides of its condenser, a pair of relay magnets, one connected in each such connection, connections from the opposite pole of said source to the other conductor, one on each side of its condenser, a relay magnet connected in each said connection, a control circuit jointly 25 controlled by the two magnets connected to the opposite conductors at one side of their condensers, a second control circuit jointly controlled by the two magnets connected to the opposite conductors at the other sides 30 of their condensers, and means for controlling the operation of said magnets.

9. An automatic common battery telephone system comprising subscribers' lines connected through the medium of a plurality of automatic step-by-step switching machines whereof one is provided with a release relay, and another with a release magnet, and a release circuit for said switches including said relay and magnet, 40 together with connections whereby talking current is furnished through one of said machines to the talking circuit established between subscribers.

10. A telephone exchange system comprising a repeater, a calling subscriber's line, a subscriber's telephone, a switch individual to said line and controllable from the subscriber's telephone, a release-circuit for conducting current to restore the said individual-switch, provided with a normally-closed switch-point, the said switch adapted for connecting the subscriber's line with the repeater, and said repeater provided with a relay for controlling said switch-point in the release-circuit, said relay being connected to supply talking current to said calling line during conversation.

11. A telephone exchange system comprising a repeater, a calling subscriber's line, a subscriber's telephone, an individual line

switch operable by the subscriber, adapted for connecting the subscriber's line with the repeater, said repeater provided with a pair of relays, and an energizing circuit for said relays, comprising the relays in series with the subscriber's line conductors.

12. A telephone exchange system comprising a repeater, a calling subscriber's line, a subscriber's telephone, an individual line-switch operable by the subscriber, adapted for connecting the subscriber's line with the repeater, said repeater provided with a pair of relays, and an energizing circuit for said relays, comprising the relay windings in series with the subscriber's telephone.

13. A telephone exchange system comprising a repeater, a calling subscriber's line, a subscriber's telephone, a subscriber's switchhook, a subscriber's induction coil, an individual line switch operable by the subscriber, adapted for connecting the subscriber's line with the repeater, said repeater provided with a pair of relays, and an energizing circuit for said relays, comprising the relays in series with the switchhook and a winding of said induction coil.

14. A telephone exchange system comprising a repeater, a calling and a called subscriber's line, a subscriber's telephone, means for extending connection to the called subscriber's line including a switch individual to the subscriber's line, controllable from the telephone, a release circuit for conducting current for releasing or restoring said individual switch, said switch adapted for connecting the subscriber's line with the repeater, said repeater provided with normally closed switch contacts and normally open switch contacts included in said circuit, means for closing the said normally open switch contacts to send current over the release circuit to restore the individual switch, means for opening the normally closed contacts to prevent a release during talking, and means having vertical and then rotary motion for seizing a called line.

15. A telephone exchange system comprising a repeater, a calling and called subscriber's line, a subscriber's telephone, means for extending connection to the called subscriber's line including an individual line switch operable by the subscriber, adapted for connecting the subscriber's line with the repeater, means having vertical and then rotary motion for seizing a called line, said repeater provided with relays, and an energizing circuit for said relays, comprising the line conductors in series.

16. A telephone exchange system comprising a repeater, a calling and a called subscriber's line, a subscriber's telephone, means for extending connection to the called subscriber's line including an individual line switch operable by the subscriber, adapted for connecting the subscriber's line with

the repeater, means having vertical and then rotary motion for seizing a called line, said repeater provided with relays, and an energizing circuit for said relays, comprising 5 the relay windings in series with the subscriber's transmitter.

17. A telephone exchange system comprising a repeater, a calling and a called subscriber's line, a subscriber's telephone, means 10 for extending connection to the called subscriber's line including a subscriber's switch-hook, a subscriber's induction coil, an individual line switch operable by the subscriber, adapted for connecting the subscriber's line 15 with the repeater, means having vertical and then rotary motion for seizing a called line, said repeater provided with relays, and an energizing circuit for said relays, comprising 20 the relays in series with the switch-hook and a winding of said induction coil.

18. A telephone exchange system comprising a repeater, a calling subscriber's telephone line including a pair of talking conductors, a subscriber's substation apparatus, 25 a switch individual to said subscriber's line and operable by the subscriber for connect-

ing said subscriber's line with said repeater, a pair of relay windings for said repeater, an energizing circuit for said relay windings, said circuit including said relay windings and said talking conductors all in series. 30

19. A telephone exchange system comprising a repeater, a calling subscriber's line, a subscriber's telephone, a subscriber's switch-hook, a subscriber's induction coil, a line switch individual to said telephone line and operable by the subscriber for connecting said line with said repeater, a pair of relay windings for said repeater, an energizing 35 circuit for said relay windings, said circuit including said relay windings, said switch-hook and a winding of said induction coil all in series. 40

In witness whereof the said JACOB W. 45 LATTIG hereunto subscribes his name this 9th day of October, A. D. 1917.

JACOB WILLIAM LATTIG.

In witness whereof the said CHARLES L. GOODRUM hereunto subscribes his name this 50 9th day of October, A. D. 1917.

CHARLES L. GOODRUM.
